CLAIM

The ornamental design for a control linkage positioning tool, as shown and described.

DESCRIPTION

FIG. 1 is a perspective view of a control linkage positioning tool embodying my new design;

FIG. 2 is a front view thereof, shown secured onto a control linkage rod. The back view of the control linkage positioning tool is a mirror image of FIG. 2. The broken line showing of a control linkage rod is for illustrative purposes only and forms no part of the claimed design;

FIG. 3 is a left side elevational view of the control linkage positioning tool;

FIG. 4 is a right side elevational view thereof;

FIG. 5 is a bottom plan view thereof; and,

FIG. 6 is a top plan view thereof.
